(57) **CLAIM**

We claim the ornamental design for a terminal configuration of a three pole plunger switch, as shown and described.

DESCRIPTION

FIG. 1 is a perspective view of the terminal configuration of a three pole plunger switch of the present invention;

FIG. 2 is a bottom plan view of the terminal configuration of a three pole plunger switch of the present invention;

FIG. 3 is an top plan view of the terminal configuration of a three pole plunger switch of the present invention;

FIG. 4 is a front elevation view of the terminal configuration of a three pole plunger switch of the present invention;

FIG. 5 is a left side elevation view of the terminal configuration of a three pole plunger switch of the present invention; and,

FIG. 6 is a right side elevation view of the terminal configuration of a three pole plunger switch of the present invention.

The broken line showing of the environment is for illustrative purpose only and forms no part of the claimed design.
